ATTORNEY

UNITED STATES PATENT OFFICE.

CAROLINE BENSON, OF PITTSBURG, PENNSYLVANIA.

CURTAIN-POLE.

No. 866,324.

Specification of Letters Patent.

Patented Sept. 17, 1907.

Application filed May 17, 1907. Serial No. 374,124.

To all whom it may concern:

Be it known that I, CAROLINE BENSON, of Pittsburgh, in the county of Allegheny and State of Pennsylvania, have invented certain new and useful Improvements in Curtain-Poles, of which the following is a specification.

The object of my invention is to provide a new and improved curtain-pole whereby the employment of hooks and pins are dispensed with.

10 To this end my invention consists in a curtain-pole, in the novel features of construction, and in the combination of parts all as fully herein described and claimed.

In the accompanying drawing, which illustrates an application of my invention, Figure 1 is a front elevational view of a curtain-pole constructed in accordance with my invention showing a curtain in place on the pole; Fig. 2, a cross-sectional view on line 2 of Fig. 1; Fig. 3, a perspective view of a portion of the 20 pole proper and coöperating parts; Fig. 4, a similar view, showing the sleeve portion in a different position from that shown by Fig. 3; Fig. 5, a cross-section taken on line 5—5 of Fig. 1; and Fig. 6, a cross-section taken on line 6—6 of Fig. 1.

25 Referring to the drawing, I designate a pole proper, made of any suitable material, preferably wood, and provided with a longitudinal slot or groove 2. This groove extends throughout the length of the pole and is preferably rectangular in cross-section, as clearly 30 shown by the drawing. Secured in the slot 2 are two flat curtain supporting rods 3. Each of these rods is pivoted at its inner end to the pole 1 by means of a pin 4 and is adapted to be swung from the open position shown in the right half of Fig. 1, to a closed position 35 as shown by the left half of said figure. The rods are each formed with a cutaway portion 5 near each end.

Located at each end of the pole I employ a cap or sleeve 6 formed with a knob 7. These sleeves are adapted to be placed over the ends of the pole proper

and over the free ends of the pivoted-rods and are designed to securely hold the rods in position. Each sleeve is formed with a slot 8 adapted to receive the free-end of one of the rods 3, and in addition thereto with a slot 9 through which a pin 10 extends.

In the drawing I have shown one curtain 11, of a pair 45 of curtains, for which my invention is particularly designed. To hang the curtains one end of a curtain is placed over one of the rods 3, and then the rod, together with the end of the curtain, is carried up into the groove or slot of the pole, the end of the rod passing 50 through the slot 8 of one of the sleeves 6. After said rod and the end of the curtain is arranged in the slot, the sleeve is turned slightly, just sufficient to carry the slot 8 out of registry with the end of the rod.

What I claim is:

1. A curtain-pole comprising a pole proper provided with a longitudinal slot rectangular in cross-section and with an engaging-pin, a pivoted-rod over which the curtain is adapted to be hung, said rod arranged in the slot, and a sleeve disposed over the end of the pole and the end of the rod and formed with a slot to receive an end of the rod and with a slot through which the pin projects.

2. A curtain-pole comprising a pole proper provided with a longitudinal slot and with an engaging-pin at each end of the pole, two curtain supporting rods, each pivoted to the pole proper at their inner ends, and a sleeve at each end of the pole extending over the end of the pole proper and the end of the pivoted rod and formed with a slot to receive an end of a rod and with a slot through which one of the pins projects.

3. A curtain pole comprising a pole proper provided with a longitudinal slot, two curtain supporting rods, each pivoted to the pole proper at their inner ends, and a sleeve at each end of the pole formed with a slot to receive the end of the pivoted-rod and extending over the 75 end of the pole proper and the end of the rod.

In testimony whereof I affix my signature in presence of two witnesses.

CAROLINE BENSON.
